UNITED STATES PATENT OFFICE.

THOMAS C. HOLT, OF MINNEAPOLIS, MINNESOTA.

BRICK-MOLDING MACHINE.

No. 857,624.

Specification of Letters Patent.

Patented June 25, 1907.

Application filed July 23, 1906. Serial No. 327,311.

To all whom it may concern:

Be it known that I, THOMAS C. HOLT, a citizen of the United States, residing at Minneapolis, in the county of Hennepin and State of Minnesota, have invented certain new and useful Improvements in Brick-Molding Machines; and I do hereby declare the following to be a full, clear, and exact description of the invention, such as will enable others skilled in the art to which it appertains to make and use the same.

My invention has for its object to provide an improved brick molding machine especially adapted for use in molding concrete bricks, and to the above ends the invention consists of the novel devices and combinations of devices hereinafter described and defined in the claims.

My invention is illustrated in the accompanying drawings wherein like characters indicate like parts throughout the several views.

Referring to the drawings:—Figure 1 is a plan view with some parts broken away and some parts sections, showing the improved machine. Fig. 2 shows the improved machine in front elevation. Figs. 3 and 4 show the improved machine in end elevation. Figs. 5, 6 and 7 are vertical sections taken through the machine on the line $x^x x^x$ of Fig. 1, and Fig. 8 is a plan view of the reversible base plate. Fig. 5 corresponds in position of parts to Fig. 3; Fig. 6 corresponds in position of parts with the full line illustration of Fig. 4; and Fig. 7 corresponds in position of parts with the dotted line illustration in Fig. 4.

The numeral 1 indicates a suitable supporting table for the improved machine. The base 2 of the machine, which is preferably bolted or otherwise rigidly secured to the table 1, is, as shown, in the form of a long rectangular flanged plate having a smooth and flat upper face, and provided at its forward edge with projecting hinge lugs 3. A reversible supplemental base plate 4 is hinged to the base plate 2, the same as shown, having projecting hinge lugs 5 that are pivotally connected by pins 6 to the hinge lugs 3 of said base plate 2. When this supplemental base plate 4 is turned upward, it rests flatwise upon the upper face of the base plate 2.

The sides or wall plates of the mold are

made up of two parts or members 7 and 8; the former of which is rigidly secured to the base plate 2, and the latter of which is rigidly secured to the reversible supplemental base plate 4. Both of the said members 7 and 8 are preferably, and as shown, provided with horizontally projecting upper and lower flanges, and their vertical wall portions are formed on zig-zag rectangular lines, as best shown in Fig. 1. The projecting angles of these zig-zagged wall plates are alined or overlapped in such a manner that they form a plurality of rectangular brick forming molds, the longitudinal diameters of which correspond to the length of the bricks; the transverse diameters of which correspond to the depth of the bricks; and the vertical diameters of which correspond to the width of the bricks. By adjusting one of the wall plates laterally with respect to the other the depth of the bricks may be varied, and hence, to arrange for such adjustment the lower horizontal flanges of the wall plate or member 8 are provided with slots 9, and machine screws 10 are passed through and screwed into the supplemental base plate 4, thereby making the said wall plate or member 8 adjustable laterally with respect to the co-operating or opposing wall plate or member 7. The free or swinging edge of the supplemental base plate 4 is formed on such zig-zag rectangular lines that, when it is turned upward and onto the face of the base plate 2, it will closely engage the zig-zag rectangular face of the wall plate or member 7, and hence will constitute bottoms to the several molds.

The wall plate 7 is formed at its ends with a vertical end plate 7^a, and the supplemental base plate 4 at its ends is formed with upwardly projecting vertical end plates 4^a. On the upper portions of the end plate 7^a are latch lugs 11. To the upper portions of the end plate 4^a latch bars 12 are pivoted at 13, and their pivotal movements are limited by slot and pin connections 14 between the said latch bars and corresponding end plates 4^a. The latch bars 12 at their free ends are formed with notches 15 that are adapted to engage their respective latch lugs 11 when the parts are in the operative positions shown by full lines in Figs. 1 to 6 inclusive. The latch bars 12 are provided with vertically spaced overlying arms 12^a. The said

parts 12—12^a constitute U-shaped brackets that are adapted to receive the ends of a pallet board 16.

The numeral 17 indicates the elongated rectangular hopper which is adapted to be closely rested upon the upper horizontal flanges of the wall plates or members 7 and 8, and which, as shown, is provided with depending fingers 18, which engage the outer edges of said flanges and hold the hopper in proper position.

Preparatory to forming the bricks the movable parts of the mold are positioned, as shown, by full lines in Figs. 1, 2, 3 and 5, and the hopper 17 is placed in position as shown in the said figures. The concrete, composed of wet sand and cement, is thrown into the hopper and into the several brick forming molds, and after the material has been properly tamped within the molds, the hopper is removed, and the surplus concrete is removed from the tops of the molds, and the upturned edges of the bricks within the molds are troweled off and smoothed. Then a pallet board 16, (of which pallet boards a large number may be employed in the machine) is placed within the receiving crotches formed by the latch bars 12 and their extensions 12^a. Then the supplemental base plate 4, together with the parts carried thereby, are turned pivotally upside down, or into the positions shown by full lines of Fig. 7 and the dotted lines of Fig. 4. This pivotal movement of the parts, not only carries the formed bricks away from the fixed or relatively stationary wall plate 7, but turns the bricks edge for edge, and transfers the same from the supplemental base plate 4 to the pallet board 16.

It is further important to note that when the parts are turned upside down, as shown in Fig. 7, the combined latches and pallet board holders 12—12^a move pivotally downward with respect to the supplemental base plate 4, and thereby drop the upper ends of the bricks slightly away from the said base plate 4, so that when the bricks are removed by the pallet board they will not be rubbed against the said plate 4, or any other part of the mold for that matter.

With the above described molding machine wherein the bricks are formed with one edge at the bottom of the mold, it is a very easy matter to form the bricks with ornamental outer edge faces, or to form the same with faces constructed of ornamental or high grade material, or in fact, of any other material which differs from the main body portion of the bricks. For instance, by first sifting a small amount of wet sand or pulverized marble into the bottoms of the molds, and thereafter filling the molds with the concrete, bricks may be formed with their faced edges, that is their edges which are exposed to view in a finished wall, having the appear-

ance of white sand bricks or pulverized marble bricks.

The machine above described is of comparatively small cost, and may be very easily and rapidly operated, and in practice has been found highly efficient for the purposes had in view.

What I claim is:—

1. In a molding machine, the combination with a supporting frame, of a reversible base plate supported thereby, and a pair of wall forming mold plates formed on zigzag rectangular lines, and one of which wall forming mold plates is secured to and is reversible with said reversible base plate, and the other of which is independently supported from said supporting frame, substantially as described.

2. In a molding machine, the combination with a supporting frame, of a reversible base plate hinged thereto, and a pair of coöperating wall forming mold plates formed on zigzag rectangular lines and coöperating to form a multiplicity of molds, one of which wall plates is secured to and reversible with said reversible base plate, and the other of which is independently supported from said supporting frame, and which reversible base plate projects beyond the wall plate which is secured thereto to form bottoms to the several molds, substantially as described.

3. In a molding machine, the combination with a fixed bed and a reversible base plate hinged thereto, of a pair of coöperating wall forming mold plates secured one to said fixed bed and the other to said reversible base plate, and a pallet board holding device carried by said reversible base plate and having a limited movement thereon and operating when said base plate is turned upside down to permit said pallet board to be lowered with respect to said base plate, substantially as and for the purposes set forth.

4. In a molding machine, the combination with a base and a reversible base plate hinged thereto, of a pair of coöperating wall forming mold plates, secured one to said base and the other to said reversible base plate, and U-shaped bars carried by said reversible base plate and having limited pivotal movements with respect thereto, and which U-shaped bars are adapted to hold a pallet board, and portions of which are arranged for co-operation with latch lugs on the fixed wall forming mold plates, substantially as described.

5. In a molding machine, the combination with a fixed bed and a reversible base plate hinged thereto, of a pair of wall forming mold plates secured one to said fixed bed and the other to said reversible base plate, the opposing faces of which wall forming mold plates are formed on zigzag rectangular lines and the free edge of which reversible base plate is also formed on zigzag rectangular lines and projects beyond the wall forming

mold plate which is secured thereto, and when said base plate is in operative position coincides with the zigzag face of the relatively fixed wall forming mold plate, substantially as described.

6. In a molding machine, the combination with a fixed bed, of a pair of wall forming mold plates formed on zigzag rectangular lines, one of which wall forming mold plates, is adjustable toward and from the coöperating zigzag wall forming mold plate in a direction parallel to the transverse end walls of the molds formed by the coöperating wall plates, to thereby set the said mold plates to form bricks of different depth or thickness, substantially as described.

7. In a molding machine, the combination with a fixed bed or support, of a reversible base plate hinged thereto, and a pair of wall

forming mold plates formed on zigzag rectangular lines, one of which wall plates is rigidly but adjustably secured to the said reversible base plate, and the other of which is independently supported from said bed plate or support, and which adjustable wall plate is adjustable in a direction parallel to the transverse end walls of the molds formed by the coöperating wall plates, to thereby set the said wall plates to form bricks of different depths or thickness, substantially as described.

In testimony whereof I affix my signature in presence of two witnesses.

THOMAS C. HOLT.
